UNITED STATES PATENT OFFICE.

CHARLES A. KENDALL, OF CONCORD, NEW HAMPSHIRE.

REVERSIBLE MAIL-ASSORTING TABLE.

SPECIFICATION forming part of Letters Patent No. 413,947, dated October 29, 1889.

Application filed October 25, 1888. Serial No. 289,128. (No model.)

To all whom it may concern:

Be it known that I, CHARLES A. KENDALL, a citizen of the United States, residing at Concord, in the county of Merrimac and State 5 of New Hampshire, have invented certain new and useful Improvements in Reversible Mail-Assorting Tables, of which the following is a specification.

This invention relates to tables designed to 10 occupy the center of a mail-car; and the object of the invention is to provide a table which can be adjusted so as to be used either side up, and when not in use may be placed in a position entirely out of the way of a mail 15 agent without being removed from its supports.

The invention consists of the novel devices 20 clearly set forth in the following specification and claims, and illustrated in accompanying drawings, forming an inseparable part thereof, of which—

Figure 1 shows an interior view of a mail-car to which my improved table is applied. Fig. 2 shows one of the end supports in 25 enlarged sectional side elevation and a portion of my improved table attached. Fig. 3 is a cross-sectional view of same, also enlarged. Fig. 4 is an enlarged broken end view.

Similar letters designate like parts.

In the most approved type of mail-car in 30 daily use throughout the United States iron bars running horizontally and supported upon iron brackets secured to the side walls are fitted with numerous metallic hooks, which 35 may be slid thereon to various points for conveniently holding open mail-bags, and above these are arranged various pigeon-holes and tills for holding loose mail. As there are three tiers of the sliding hooks on each side 40 of the car for holding mail-bags, there is insufficient space remaining in the center for a permanent or stationary assorting-table and a passage-way at either side; hence portable tables have been used, and these must be 45 moved about and from side to side as occasion requires; but by the use of my improvements these troubles are avoided, as will be seen by following the description of the various parts by reference-letters.

50 A represents a portion of a car, B the car-floor, and C the longitudinal sills.

D D are the iron brackets, to which bars

carrying suitable hooks for holding mail-bags E may be attached. Above these at either side are shown cases F F', which may contain 55 suitable pigeon-holes or tills for parcels or heavy mail-matter.

My improvements comprise a reversible table G, having a rim g on both sides and all the way around, pivoted at its ends near one 60 edge to vertical supports or posts H, and adapted to be held horizontally either side up by aid of the rods I, having their upper ends pivoted to the ends of said table and their lower ends loosely fitting a bolt or stud J, its 65 head j being confined within a groove h, formed in the outer face of either support H by an iron plate K, having a long slot k, in which said stud J travels. A nut j' is fitted to the threaded end of said stud outside of the 70 lower perforated end of the rod I. The plate K may be secured to the post H by ordinary wood-screws k', and its slot k is made long enough to permit the rod I to rise, as required, when the table is reversed from side to side. 75

In order to afford a free passage-way on either side of the posts H, the reversible table G may be held in a vertical position, as indicated by dotted lines in Fig. 1, by a suitable catch for sustaining the rods I in an upright position. A device capable of performing this function is shown in the drawings, and consists of a forked piece L, pivoted to ears formed upon a plate M, so that its prongs l, when turned outward or horizontally, may 85 bear against either side of said rod I and confine it therein, as best shown in Fig. 4, in which view the piece L is shown in dotted lines as when closed up against the post H.

The supports or posts H may be mortised 90 into a short timber C', secured between the two center car-sills C, or angle-irons N, screwed to three or more sides of each post and to the floor of a car, may be alone depended upon for their supports. This construction pos- 95 sseses among other advantages that of providing two extra tiers of hooks for holding mail-bags, as best shown in Figs. 2 and 3. The double hooks P are fitted loosely to an iron bar R, supported at either end by the 100 posts H, and bags may be hung upon either side, which in practice would be opposite to the table, as in Fig. 1.

It is immaterial how the table is pivoted to

the uprights or posts; but a strong and convenient method is to secure angle-irons N to the top of the posts H and perforate their vertical sides for the reception of a stud g^2 , formed 5 upon a plate g' , which may be secured to the table G by screws.

Having described my improvements, what I claim as new, and desire to secure by Letters Patent, is—

- 10 1. The combination, with supporting-stands having angle-irons secured to their top, the vertical portion of which contains a single perforation, of a reversible table having rims on both sides and all around, plates secured to each end of said table and provided with studs for entering the perforation of said angle-iron, and brace-rods having one end pivoted to either end of said table and the other end capable of vertical movement upon said supporting-standards.
- 15 2. The combination of supporting-stands provided with angle cap-irons having in their vertical portions a single perforation, a reversible table having rims on both sides and all around hinged at either end near one side to said angle cap-irons, brace-rods having

one end pivoted to either end of said table and the opposite end connected to either supporting-standard and capable of vertical movement thereon, and means for securing 30 said brace-rods and reversible table in a vertical position, for the purpose set forth.

3. The combination of supporting-stands provided with angle cap-irons having in their vertical portions a single perforation, 35 one or more bars running horizontally between said standards, having adjustable mail-bag hooks mounted thereon, a reversible table hinged to said angle cap-irons, and brace-rods connecting said table with said standards in 40 a manner whereby the said table may be securely adjusted to a vertical position and to a horizontal position at either side of said standards, substantially in the manner specified.

In testimony whereof I affix my signature in presence of two witnesses.

CHARLES A. KENDALL.
